(57) **CLAIM**

The ornamental design for a thrust bumper, as shown and described.

DESCRIPTION

FIG. 1 is a front perspective view of the thrust bumper of the present invention;

FIG. 2 is a back perspective view thereof;

FIG. 3 is a front plan view thereof;

FIG. 4 is a sectional view thereof taken along line 4-4 in FIG. 11;

FIG. 5 is a back plan view;

FIG. 6 is a sectional view thereof taken along line 6-6 in FIG. 12;

FIG. 7 is a side plan view;

FIG. 8 is a the opposite side plan view thereof;

FIG. 9 is a sectional view thereof taken along line 9-9 of FIG. 3;

FIG. 10 is a sectional view thereof taken along line 10-10 of FIG. 3;

FIG. 11 is an adjacent side plan view thereof;

FIG. 12 is the opposite side plan view thereof;

FIG. 13 is a sectional side plan view of FIG. 11 taken along line 13-13 of FIG. 7;

FIG. 14 is a sectional side plan view of FIG. 12 taken along line 14-14 of FIG. 7;

FIG. 15 is a front perspective view of the thrust bumper of FIG. 1 with an extension;

FIG. 16 is an exploded view thereof;

FIG. 17 is a side plan view thereof;

FIG. 18 is a sectional view thereof taken along line 18-18 of FIG. 19;

FIG. 19 is an adjacent side plan view thereof;

FIG. 20 is a sectional view thereof taken along line 20-20 in FIG. 17;

FIG. 21 is a perspective view of the thrust bumper of FIG. 1 in a position of use; and,

FIG. 22 is a sectional view thereof taken along line 22-22 in FIG. 21.

The claimed design and illustrations shown in the drawings depict a thrust bumper.

The broken lines depict environment and form no part of the claim. The unevenly dashed lines with arrows and numbers depict the cut lines of the sectional views and form no part of the claim. The horizontal dashed lines in FIG. 18 and FIG. 20 depict environmental subject matter in the sectional view and form no part of the claim.

1 Claim, 15 Drawing Sheets
